ADJUSTABLE INDOOR TELEVISION ANTENNA OR SIMILAR ARTICLE

Roger Mark Singer, New York, N.Y., assignor to Snyder
Manufacturing Company, Philadelphia, Pa., a corpora-
tion of Pennsylvania

Filed Nov. 1, 1963, Ser. No. 77,240

Term of patent 14 years

(Cl. D26—14)

FIG. 1.

FIG. 5.

FIG. 2.

FIG. 3.

FIG. 4.

FIG. 1 is a perspective view of an adjustable indoor television antenna or similar article, showing my new design with the two telescoping pivoted rod antenna elements partially extended;

FIG. 2 is a left side elevational view, to an enlarged scale, with the rod antenna elements in another position, the opposite side being substantially a mirror image thereof;

FIG. 3 is a top plan view, to an enlarged scale, with the rod antenna elements positioned as in FIG. 2;

FIG. 4 is a front elevational view, to an enlarged scale, with the rod antenna elements positioned as in FIGS. 2 and 3; and

FIG. 5 is a rear elevational view thereof, to a reduced scale, with the rod antenna elements in still another position.

Portions of the drawing figures are diagonally lined to

indicate transparency. The legible matter shown in broken lines in FIG. 3 is for illustrative purposes only.

I claim:

The ornamental design for an adjustable indoor television antenna or similar article, substantially as shown and described.
